UNITED STATES PATENT OFFICE

HOWARD M. BARBER, OF PAWCATUCK, CONNECTICUT, ASSIGNOR TO C. B. COTTRELL & SONS COMPANY, OF WESTERLY, RHODE ISLAND, A CORPORATION OF DELAWARE

ROTARY PRINTING PRESS

Application filed December 1, 1928. Serial No. 323,038.

In multicolor rotary printing presses it is usual to provide a brush which is moved into and out of coaction with the impression cylinder for laying the successively fed sheets smoothly thereon before they pass under the form cylinders to be printed. It is usual to bring this brush into contact with each sheet just after the advance edge of the sheet has passed the brush, so that the brush will not 5 muss or tear the sheet along its advance edge. In rotary printing presses of this type in which means, operated when the sheet feeder fails to present a sheet, are provided for automatically causing the impression cylinder grippers to remain closed on the printed sheet beyond its delivery point, it is necessary that the brush should not be brought into its operative position in contact with the said freshly printed sheet as such contact would 10 cause the ink on the sheet to be transferred to the brush, so that when the press again starts the so-inked brush would smear and ruin a considerable number of successively fed sheets.

The object of my invention therefore, is to provide means, operated by the failure of the sheet feeder to present a sheet, for not only causing the impression cylinder grippers to retain the freshly printed sheet on the impression cylinder beyond its delivery point to protect the cylinder blanket, but also for holding the brush in its inoperative position out of contact with said freshly printed sheet, the brush being locked in such inoperative 25 position until it is released by the manually operated means for causing the resetting of the gripper operating cams.

In the accompanying drawings I have shown my invention as applied to the sheet 40 feeder controlled gripper mechanism set forth and claimed in my copending application, filed October 26th, 1928, Serial No. 315,304.

Fig. 1 of the drawings represents a detail 45 side elevation showing so much of a rotary printing press of the type set forth, as will give a clear understanding of my invention; the parts being in their normal operative positions.

Fig. 2 represents a similar elevation with

the parts in the positions they assume when the sheet feeder has failed to present a sheet to the feeding cylinder grippers.

Fig. 3 represents a fragmentary view showing the brush locked in its inoperative 55 position after the high part of the brush operating cam has moved past the stud or roller on the brush lever arm.

Fig. 4 represents a detail end elevation with the parts in the positions shown in 60 Fig. 1.

The impression cylinder of the printing press is denoted by 1, its shaft by 2 and its sheet grippers by 3. The sheet feeding cylinder is denoted by 4, its shaft by 5 and its 65 sheet grippers by 6. The sheet delivery cylinder is denoted by 7, its shaft by 8 and its sheet grippers by 9.

The impression cylinder gripper operating cam 10 is pivoted at 11 so that it may be 70 swung into and out of its normal operative position in the path of the spring pressed gripper operating lever 12 for controlling the operation of the impression cylinder grippers 3, both at their receiving point from the 75 sheet feeding cylinder grippers 6 and also at their delivery point to the delivery cylinder grippers 9.

The delivery cylinder gripper operating cam 13 is pivoted at 14 so that it may be 80 swung into and out of its normal operative position in the path of the spring pressed gripper operating lever 15 for controlling the operation of the delivery cylinder grippers 9 at their receiving point from the impression 85 cylinder grippers 3.

These movable gripper controlling cams 10 and 13 are interconnected through the two armed rock lever 16, 17 and rods 18, 19 to move together into and out of their operative 90 positions.

The spring pressed tumbler cam 20 carried by the grippers 6 of the sheet feeding cylinder 4 is operated by the usual tumbler operating pin 21 at their sheet receiving 95 point to close the grippers on a sheet as it is fed in by an automatic sheet feeder of any well known or approved form, the portions which are shown in the accompanying drawings being denoted by 22. This tumbler cam 100

20 is normally operated at the transfer point from the feeding cylinder to the impression cylinder by an endwise movable tumbler operating pin 23 to open the feeding cylinder 5 grippers 6 for permitting the sheet to be transferred to the impression cylinder grippers 3. The grippers 6 then normally remain open until they are again closed on the next succeeding sheet fed from the feeder by the 10 coaction of the tumbler cam 20 with the pin 21.

A second endwise movable tumbler operating pin 24 is arranged in proximity to the pin 23 in position to be moved into the path 15 of the tumbler cam 20 as the pin 23 is moved out of said path in the event that the feeder fails to present a sheet to the feeding cylinder grippers, thereby holding the grippers closed until they have passed their transfer point 20 to the impression cylinder grippers. The device for moving these pins 23, 24 endwise simultaneously in opposite directions comprises a pin controlling cam lever pivoted at 25 and having a cam 26 engaging the pin 23 and a second cam 27 engaging the pin 24, 25 the cams being so inclined that as one of the pins is withdrawn from the path of the tumbler cam 20, the other pin will be projected into said path.

30 This pin controlling cam lever is operated by and from the impression cylinder gripper operating cam 10 through a connecting rod 28 secured at one end to the arm 29 of the pin controlling lever and at its other end to the cam 10 at the point 20.

The means which I have shown for controlling the operation of the feeding, impression and delivery cylinder grippers, is as follows:—A two armed cam controlling lever 31, 32, is carried by the rock shaft 33 and has its arm 31 connected by a swinging link 34 to the cam 10, thereby forming a toggle joint connection therewith. The other arm 32 of this lever is normally engaged by one arm 35 of a latch pivoted at 36, the other arm 37 of which latch is connected by a rod 38 to the rocking arm 39 of an automatic throw-off mechanism of any well known or approved form, operating in the usual manner to stop the feeder and the press when the feeder fails to present a sheet to the feeding cylinder grippers. A spring 40 yieldingly holds the latch in position to engage and lock the arm 32 of the cam controlling lever, and a spring 41 exerts pressure on the arm 31 of the cam controlling lever for breaking the toggle joint connection between it and the cam 10 when the latch arm 35 is released from its engagement with the lever arm 32 by the operation 55 of the throw-off mechanism for swinging the interconnected cams 10 and 13 out of their normal operative positions.

The sheet smoothing device is herein shown as a brush 42 which is carried by two arms 43, 44, projecting from a cross rock shaft 45,

which brush is arranged to be brought into and out of its operative position for engaging successively fed sheets on the impression cylinder immediately back of their advance edges to lay them smoothly upon the impression cylinder.

The means which I have shown for controlling the movement of the sheet smoothing brush is as follows:

The cross rock shaft 45 which carries the brush is provided with a lever arm 46 having a stud or roller 47 normally engaged at all times by the circumferential face of a disc cam 48 fast on the shaft 5 of the sheet feeding cylinder 4. The high part of this cam is so positioned with respect to the position of the impression cylinder grippers that it will move the brush away from the impression cylinder until the advance edge of the sheet thereon has passed the brush, when the brush will be allowed to move back into position to smooth out the sheet on the impression cylinder before the sheet is subjected to the printing operation. A spring 49 engaged with the arm 46 yieldingly holds the brush 42 in its operative position in contact with the impression cylinder and the stud or roller 47 in contact with the rotary cam 48. The cross rock shaft 45 is also provided with another lever arm 50 which has a notch 51 for receiving the end of one arm 52 of a latch pivoted at 53, the other arm 54 of which latch is provided with an adjustable stop, in the present instance a screw 55, the inner end of which is yieldingly held in engagement 95 with the rocking cam 10 by a spring 56.

The operation:—When, from any cause, the feeder fails to present a sheet to the sheet feeding cylinder grippers, the automatic throw-off mechanism will operate in the usual manner to stop the feeder and the press. The rocking of the arm 39 of the throw-off mechanism will cause the latch 35, 37 to swing its arm 37 out of locking engagement with the arm 32 of the cam controlling lever 31, 32, thereby permitting the spring 41 to break the toggle joint connection between the cam controlling lever and the cam 10, thus causing the interconnected cams 10 and 13 to swing out of their normal operative positions in the paths of the impression and delivery cylinder gripper levers 12 and 13 and allowing the impression and delivery cylinder grippers to remain closed as they pass their transfer point. This will cause the impression cylinder grippers to retain the freshly printed sheet on the cylinder beyond its delivery point and present it in position for a second impression while the press is stopping; thereby protecting the cylinder blank.

At the same time, the movement of the impression cylinder gripper controlling cam 10 will move the tumbler pin controlling lever to cause it to move the tumbler pin 23 end-

wise out of the path of the feeding cylinder gripper tumbler cam 20 and the tumbler pin 24 endwise into the said path so that the feeding cylinder grippers will not be opened 5 until they have passed their transfer point to the impression cylinder grippers, thus protecting the advance edge of the freshly printed sheet held on the impression cylinder from becoming so torn or otherwise mutilated 10 by the feeding cylinder grippers as to prevent it from being subsequently delivered when the press is again started. This inward swinging movement of the cam 10 will permit the latch 52, 54 to swing under the influence of its spring 56 to bring the arm 52 into locking engagement with the brush lever arm 50 and thereby lock the brush 42 in its inoperative position out of contact with the freshly printed sheet on the impression cylinder; it being understood that the brush has already been moved to this position by the contact of the high part of the cam 48 with the stud or roller 47 on the brush lever arm 46. It will be seen that as the high part of 25 the cam leaves the stud or roller 47, the latch arm 52, because of its engagement with the brush lever arm 50, will prevent the brush from swinging back under the influence of its spring 49, into contact with the freshly 30 printed sheet retained on the impression cylinder.

The means which I have shown for restoring the parts to their operative positions is a hand lever 57 fast on the shaft 33. This 35 lever may be swung to rock the cams 10 and 13 back into the paths of their respective gripper operating levers. At the same time the cam 10 because of its engagement with the adjustable stop 55 will, in its outward 40 movement, unlock the arm 52 of the latch 52, 54, thereby releasing the brush lever 50 and permitting the stud or roller 47 to swing back into contact with its operating cam 48.

It will be understood that the means for 45 controlling the movements of the grippers on the feeding, impression and delivery cylinders forms the subject matter of my copending application hereinabove referred to, the present application being directed to the 50 means for locking the sheet smoothing device in its inoperative position when the feeder fails to present a sheet, also to the manually operated means for unlocking the device before restarting the press.

55 It is evident that various changes may be resorted to in the construction, form and arrangement of the several parts without departing from the spirit and scope of my invention, hence I do not wish to be limited to 60 the particular embodiment herein shown and described, but

What I claim is:—

1. In a rotary printing press equipped with a sheet feeder, an impression cylinder, a sheet 65 smoothing device, means for moving it into

and out of its operative position and means, operable when the feeder fails to present a sheet, for locking the said device in its inoperative position.

2. In a rotary printing press equipped 70 with a sheet feeder, an impression cylinder, a sheet smoothing device, means for moving it into and out of its operative position, means, operable when the feeder fails to present a sheet, for locking the said device in its inoperative position, and manually operated means for unlocking the sheet smoothing device. 75

3. In a rotary printing press equipped with a sheet feeder having a throw-off mechanism, 80 an impression cylinder, a sheet smoothing device, means for moving it into and out of its operative position and means, actuated by the throw-off mechanism when the feeder fails to present a sheet, for locking the said device in its inoperative position. 85

4. In a rotary printing press equipped with a sheet feeder having a throw-off mechanism, 90 an impression cylinder, a sheet smoothing device, means for moving it into and out of its operative position, means, actuated by the throw-off mechanism when the feeder fails to present a sheet, for locking the said device in its inoperative position, and manually operated means for unlocking the sheet smoothing 95 device.

5. In a rotary printing press equipped with a sheet feeder, an impression cylinder, a sheet smoothing device, means for moving it into and out of its operative position and means, 100 operable when the feeder fails to present a sheet, for causing the impression cylinder to retain the freshly printed sheet thereon beyond its delivery point and also for locking the said device in its inoperative position. 105

6. In a rotary printing press equipped with a sheet feeder, an impression cylinder, a sheet smoothing device, means for moving it into and out of its operative position, means, operable when the feeder fails to present a sheet, for causing the impression cylinder to retain the freshly printed sheet thereon beyond its delivery point and also for locking the said device in its inoperative position, and manually operated means for unlocking the sheet smoothing device. 110 115

7. In a rotary printing press equipped with a sheet feeder having a throw-off mechanism, an impression cylinder, a sheet smoothing device, means for moving it into and out of its operation position and means, actuated by the throw-off mechanism when the feeder fails to present a sheet, for causing the impression cylinder to retain the freshly printed sheet thereon beyond its delivery point 120 and also for locking the said device in its inoperative position. 125

8. In a rotary printing press equipped with a sheet feeder having a throw-off mechanism, an impression cylinder, a sheet smoothing 130

- device, means for moving it into and out of its operative position means, actuated by the throw-off mechanism when the feeder fails to present a sheet, for causing the impression cylinder to retain the freshly printed sheet thereon beyond its delivery point and also for locking the said device in its inoperative position, and manually operated means for unlocking the sheet smoothing device.
9. In a rotary printing press equipped with a sheet feeder, an impression cylinder, its grippers, a sheet smoothing device, means for moving it into and out of its operative position and means, operable when the feeder fails to present a sheet, for causing the impression cylinder grippers to retain the freshly printed sheet on the cylinder beyond its delivery point and also for locking the said device in its inoperative position.
10. In a rotary printing press equipped with a sheet feeder, an impression cylinder, its grippers, a sheet smoothing device, means for moving it into and out of its operative position means, operable when the feeder fails to present a sheet, for causing the impression cylinder grippers to retain the freshly printed sheet on the cylinder beyond its delivery point and also for locking the said device in its inoperative position, and manually operated means for unlocking the sheet smoothing device.
11. In a rotary printing press equipped with a sheet feeder having a throw-off mechanism, an impression cylinder, its grippers, a sheet smoothing device, means for moving it into and out of its operative position and means, actuated by the throw-off mechanism when the feeder fails to present a sheet, for causing the impression cylinder grippers to retain the freshly printed sheet on the cylinder beyond its delivery point and also for locking the said device in its operative position.
12. In a rotary printing press equipped with a sheet feeder having a throw-off mechanism, an impression cylinder, its grippers, a sheet smoothing device, means for moving it into and out of its operative position, means actuated by the throw-off mechanism when the feeder fails to present a sheet, for causing the impression cylinder grippers to retain the freshly printed sheet on the cylinder beyond its delivery point and also for locking the said device in its inoperative position, and manually operated means for unlocking the sheet smoothing device.
13. In a rotary printing press equipped with a sheet feeder, an impression cylinder, its grippers, a controlling cam therefor movable into and out of its operative position, a latch normally locking said cam in its operative position, a sheet smoothing device, means for moving it into and out of its operative position, a latch for locking said device in its inoperative position and means, operable when the feeder fails to present a sheet, for moving the first named latch out of its locking position to permit the cam to move to its inoperative position and also for moving the second named latch into its locking position, to hold the sheet smoothing device in its inoperative position.
14. In a rotary printing press equipped with a sheet feeder, an impression cylinder, its grippers, a controlling cam therefor movable into and out of its operative position, a latch normally locking said cam in its operative position, a sheet smoothing device, means for moving it into and out of its operative position, a latch for locking said device in its inoperative position and means, operable when the feeder fails to present a sheet, for moving the first named latch out of its locking position to permit the cam to move to its inoperative position and also for moving the second named latch into its locking position, to hold the sheet smoothing device in its inoperative position.
15. In a rotary printing press equipped with a sheet feeder having a throw-off mechanism, an impression cylinder, its grippers, a controlling cam therefor movable into and out of its operative position, a latch normally locking said cam in its operative position, a sheet smoothing device, means for moving it into and out of its operative position, a latch for locking said device in its inoperative position and means, actuated by the throw-off mechanism when the feeder fails to present a sheet, for moving the first named latch out of its locking position to permit the cam to move to its inoperative position and also for moving the second named latch into its locking position, to hold the sheet smoothing device in its inoperative position.
16. In a rotary printing press equipped with a sheet feeder having a throw-off mechanism, an impression cylinder, its grippers, a controlling cam therefor movable into and out of its operative position, a latch normally locking said cam in its operative position, a sheet smoothing device, means for moving it into and out of its operative position, a latch for locking said device in its inoperative position and means, actuated by the throw-off mechanism when the feeder fails to present a sheet, for moving the first named latch out of its locking position to permit the cam to move to its inoperative position and also for moving the second named latch into its locking position, to hold the sheet smoothing device in its inoperative position.
17. In a rotary printing press equipped with a sheet feeder, sheet feeding, impression and delivery cylinders, their grippers, con-

- trolling cams for said grippers movable into and out of their operative positions, a latch normally locking said cams in their operative positions, a sheet smoothing device, means for moving it into and out of its operative 5 position, a latch for locking said device in its inoperative position and means, operable when the feeder fails to present a sheet, for moving the first named latch out of its locking position to permit the cams to move to 10 their inoperative positions and also for moving the second named latch into its locking position, to hold the sheet smoothing device in its inoperative position.
18. In a rotary printing press equipped 15 with a sheet feeder, sheet feeding, impression and delivery cylinders, their grippers, controlling cams for said grippers movable into and out of their operative positions, a latch normally locking said cams in their operative 20 positions, a sheet smoothing device, means for moving it into and out of its operative position, a latch for locking said device in its inoperative position, means, operable when the feeder fails to present a sheet, 25 for moving the first named latch out of its locking position to permit the cams to move to their inoperative positions and also for moving the second named latch into its locking 30 position, to hold the sheet smoothing device in its inoperative position, and a common manually operated means for returning the latches to their original positions.
19. In a rotary printing press equipped 35 with a sheet feeder having a throw-off mechanism, sheet feeding, impression and delivery cylinders, their grippers, controlling cams for said grippers movable into and out of their operative positions, a latch normally locking said cams in their operative 40 positions, a sheet smoothing device, means for moving it into and out of its operative position, a latch for locking said device in its inoperative position, and means, actuated by the throw-off mechanism when the feeder 45 fails to present a sheet, for moving the first named latch out of its locking position, to permit the cams to move to their inoperative positions and also for moving the second named latch into its locking position, to hold 50 the sheet smoothing device in its inoperative position.
20. In a rotory printing press equipped 55 with a sheet feeder having a throw-off mechanism, sheet feeding, impression and delivery cylinders, their grippers, controlling cams for said grippers movable into and out of their operative positions, a latch normally locking said cams in their operative 60 positions, a sheet smoothing device, means for moving it into and out of its operative position, a latch for locking said device in its inoperative position, means, actuated by the throw-off mechanism when the feeder fails to present a 65 sheet, for moving the first named latch out
- of its locking position, to permit the cams to move to their inoperative positions and also for moving the second named latch into its locking position, to hold the sheet smoothing device in its inoperative position, and a common manually operated means for returning the latches to their original positions. 70
- In testimony, that I claim the foregoing as my invention, I have signed my name this 28th day of November, A. D. 1928.
